CARRIER STRIP FOR HOLDING FASTENERS

George J. Gallee, Rosemont, Allen R. Obergfell, Park Ridge, and Richard H. Doyle, Mount Prospect, Ill., assignors to Fastener Corporation, Franklin Park, Ill., a corporation of Illinois

Filed June 19, 1967, Ser. No. 7,520

Term of patent 14 years

(Cl. 54—1)

FIG. 1

FIG. 2

FIG. 3

FIG. 5

FIG. 4

FIG. 6

FIG. 1 is a perspective view illustrating one side of a carrier strip for holding fasteners embodying our new design;

FIG. 2 is a perspective view illustrating the opposite side of the carrier strip of FIG. 1;

FIG. 3 is an end view of the carrier strip of FIG. 1;

FIG. 4 is a side elevational view of the same side of the carrier strip as shown in FIG. 1;

FIG. 5 is a side elevational view illustrating the same side of the carrier strip as shown in FIG. 2;

FIG. 6 is a top plan view of the carrier strip of FIG. 1. The broken lines are for illustrative purposes only.

We claim:

The ornamental design for a carrier strip for holding fasteners, substantially as shown and described.
